UNITED STATES PATENT OFFICE.

EDWARD F. CARR, OF LOS ANGELES, CALIFORNIA.

GARMENT-DISPLAY RACK.

1,177,482.

Specification of Letters Patent. Patented Mar. 28, 1916.

Application filed April 21, 1914. Serial No. 833,365.

To all whom it may concern:

Be it known that I, EDWARD F. CARR, a citizen of the United States, residing at the city of Los Angeles, in the county of Los Angeles and State of California, have invented new and useful Improvements in Garment-Display Racks, of which the following is a specification.

My invention relates primarily to a rack 10 for displaying gentlemen's clothing and the object thereof is to employ simple and efficient means for that purpose in which the handling of the garments to display them is reduced to a minimum.

15 A further object is to provide a rack in which the garments may be easily and quickly covered or inclosed to protect the same from dust and the like.

I accomplish these objects by the rack described herein and illustrated in the accompanying drawings forming a part hereof in which:—

Figure 1 is a sectional end elevation of my improved rack. Fig. 2 is a fragmentary 25 top plan of so much of my rack as is necessary to properly illustrate my invention. Fig. 3 is a perspective detail of a portion of the hanger arm bar. Fig. 4 is a perspective detail of one end of the side rails which 30 support the top of the rack. Fig. 5 is a view in perspective of one of the hanger arms used with my improved rack.

In the drawings forming a part of this application the base member is composed of 35 longitudinal side bars 7 which are joined together at intervals by cross bars 8. Bars 8 have cut in the upper edges thereof a recess 9 in which is received a longitudinally extending base plate 10. A floor 11 is secured upon the upper edges of bars 7 and 40 8 and also secured to plate 10.

Corner posts 12 are provided at each corner of the base and support the top 13. At each end are provided transparent panels 45 14 which extend from the base to the top between the corner posts. Plate 10 and floor 11 have sockets 15 cut therein where they pass over cross bars 8 in which are received the lower ends 16 of center posts 17 which 50 ends are reduced in size and are square. The main portion of these posts is round and extends upwardly and the upper end 18 is reduced in size and passes through a square socket 19 in hanger arm bar 20 and has 55 mounted on the upper end a cap 21. Cap 21 has transversely extending arms 22 project-

ing outwardly therefrom which have mounted upon their ends the side rails 23. These caps are secured upon the posts by screws 24. Side rails 23 are preferably of 60 angle iron and extend from end to end of the rack and are secured to the ends as best shown in Fig. 4. Buttons 25 are secured to the inner sides of the downwardly extending portions of the side rails and are adapted to 65 receive thereon a curtain or cover (not shown) when it is desired to protect the garments from dust. Hanger arm bar 20 is preferably formed of a center piece 26 of wood and has a casing 27 of metal surrounding the same. Where the rack is longer than the ordinary length of the metal the casing is so constructed that the top thereof overlaps the joint in the wood at one side and the bottom of the casing overlaps 70 75 the joint at the other side. When such a joint is made socket 19 is formed in the two adjoining ends of the wood as best shown in Fig. 3.

The wood and metal casing are secured 80 together by screws or other means. A transparent top 13, preferably of glass, is supported upon the side rails and the end of the rack and may be secured thereto in any desired manner. Hanger arms are mounted 85 to swing on said hanger arm bar. The body of the hanger arm is preferably formed of two members 27 and 28 and have secured to their outer ends a hook 29 by rivets or otherwise which serves to connect the same. 90 Hook 29 extends downwardly from member 28 and is bent outwardly and then downwardly and terminates in hooks 30. The other ends of members 27 and 28 are twisted 95 at right angles and are connected at a distance from their ends by a separator rod 31 the ends of which are riveted in holes in each of said members. Members 27 and 28 are provided at their ends with holes 32 through which are passed bolts 33 to secure the same to the hanger bar. Washers 34 are provided on bolts 33 between the inner sides of these arms and the hanger arm bar. A slide hook 35 is slidably mounted between members 27 and 28 and is held adjustable at the required position by a U-shaped clip 36 which is pivotally mounted at the ends of its legs upon the sides of this slide. The other end of clip 36 is received in notches 37 in the upper edge of member 27, to hold the hook in its adjusted position. A hanger 38 having a shank 39 may be sus-

pended from any of the hooks. Hanger 38 may be used to support a coat.

It will be observed that in the construction illustrated the hook of the hanger arm 5 farthest from the hanger arm bar, which will be called the outer hook, is rigidly secured to the arm and the inner hook slides but if desired the inner hook could be fixed to the arm and the outer one slide. It will 10 also be observed that these hooks are formed of companion members spaced apart thus making bifurcated hooks. The object of this construction is to provide hooks to support the trousers 40 on both sides of the 15 waistband. The buttons or belt straps at one fold of the waistband are secured to the fixed hook of the arm and the buttons or belt strap at the other fold of the waistband are secured to the sliding hook which is 20 then moved to make taut the waistband and then is secured by clip 35. By using a hook on the outer end of the hanger like that shown at the left in Fig. 1 a coat and trousers may be displayed from the same 25 arm. The shank of the hanger could be constructed to permit the coat to lie in a plane parallel with the trousers. By swinging the garments beneath the top a curtain (not shown) can be placed on the buttons 30 of the side rails to protect the garments from dust.

By this construction a rack is provided that can be shipped knocked down and then quickly put up in its place of use. This 35 construction permits of building the rack in sections which fit each other so that racks of great length can be quickly erected.

Center posts at the end may be used instead of corner posts but I prefer corner 40 posts as they give additional strength.

Having described my invention what I claim is:

1. A display rack comprising a base; a plurality of separated posts rigidly mounted 45 in and on the central longitudinal line of said base, said posts having tops reduced in size; ends secured to said base; a hanger bar secured to said ends and having aper-

tures along the central longitudinal line thereof into and through which pass the reduced ends of said posts; transverse arms mounted upon the tops of said posts; and a transparent top mounted upon said transverse arms, said top being secured to said ends. 55

2. In a display rack having a base and ends a hanger bar near the top thereof extending centrally and longitudinally from end to end of the rack and secured to said ends, in combination with supports for said bar intermediate its ends, said supports being secured to the base and positioned to leave the edges of the hanger bar unobstructed for the attachment thereto of hanger arms, whereby garments may be 60 displayed from both sides of the hanger bar throughout its entire length and hangers pivotally secured to said bar to swing in the plane of the top of said bar. 65

3. The combination of a display rack 70 having a hanger bar extending along the central longitudinal line beneath the top, with a hanger arm composed of two members of strap metal having the outer portions in a vertical plane and the inner portions in a horizontal plane and adapted to straddle the hanger arm bar and to be 75 pivotally secured thereto; said arm having a hook at its outer end and another hook near the inner end. 80

4. In a garment display rack a hanger arm composed of strap metal arranged into two members the inner ends of which lie in horizontal planes and the outer ends in a vertical plane; a hook rigidly secured at or near one end thereof; a sliding hook mounted at the other end to slide on and between the members of said arm; and means to hold the sliding hook in any desired position. 85

In witness that I claim the foregoing I 90 have hereunto subscribed my name this 28th day of March, 1914.

EDWARD F. CARR.
